[57] CLAIM

The ornamental design for a computer security bracket, as shown and described.

DESCRIPTION

FIG. 1 is a top perspective view of a computer security bracket showing our new design, the computer being shown in broken lines for illustrative purposes only;

FIG. 2 is a front elevational view thereof;

FIG. 3 is a rear elevational view thereof;

FIG. 4 is a top plan view thereof;

FIG. 5 is a bottom plan view thereof;

FIG. 6 is a right hand side elevational view thereof, the left side being mirror image.

FIG. 1

FIG. 2

FIG. 3

FIG. 4

FIG. 6

FIG. 5
